UNITED STATES PATENT OFFICE

JOHN N. MOCKING AND MORRIS INDECH, OF CHICAGO, ILLINOIS

ICE-CREAM CUTTER

Application filed October 29, 1929. Serial No. 403,256.

This invention relates to a device for cutting ice-cream or any other partly frozen semi-soft mass into uniform slices.

In brief the invention consists of a box-like structure having a tray for holding a brick of ice-cream or the like, means for gaging the thickness of the slices to be cut and means for removing the cut slices on said tray.

10 The principal object of the invention is to provide a device of this character for cutting a brick of ice-cream or the like into uniform slices without compressing the size of the cut slices.

15 Another object of the invention is to provide a device of this class having means to gage the thickness of the slices to be cut and intermediary engaging means to cut slices one-half the thickness produced by the first 20 mentioned gaging means.

Other objects of the invention will appear as the disclosure progresses. The drawings are intended to merely indicate a possible embodiment of the invention. It is obvious

25 that the needs of manufacture may necessitate certain mechanical changes. It is therefore not intended to limit the invention to the embodiment illustrated but rather to define such limits in the appended claim.

30 For a more general understanding of the invention attention is called to the drawings. In these drawings like parts denote like reference characters throughout the specification.

35 Figure 1 is a perspective view of the cutter.

Figure 2 is a perspective view of the cutter with the cover removed.

40 Figure 3 is a section on line 3—3 of Figure 2 showing a sliced brick of ice-cream.

Referring now to the drawings in detail, numeral 1 designates the body of the cutter formed of wall members 2 and 3, and members 4 and 5, and a bottom 6. Numeral 7 designates the cover. As noted in Figure 2 the end 4 is hinged so that it can open for moving the tray 8 which is normally housed in the body outwardly thereof. The tray 8 50 consists of a bottom 9 and an upstanding

end 10 and is wide and long enough to fit snugly in the body.

Cut in the wall members 2 and 3 are a series of slots 11 reaching down to the bottom and dividing the said wall members 55 into several equal portions. Formed in the end member 5 is a hole 12 through which a finger can be put for giving the tray an initial push outwardly.

In operation the tray 8 is placed in the box 60 and on top of the tray is placed a brick of ice-cream 13 or the like whose size is equal to the capacity of the box. The hinged end 4 is then lifted up and the cover 7 applied thereto. In this condition the product can be shipped to the customers. When it is desired to dispense the article the cover is removed and a knife, wire or other instrument is placed across the device so that it will reach from opposite slot to opposite slot and pressed 70 down until the block is fully cut into slices. The tray 8 is then moved outwardly as shown in Figure 2 so that the slices can be freely removed.

All of the cuts can be made simultaneously or one at a time. When the cuts are made one at a time the tray is moved the distance equal from one slot to the adjacent slot for each cut. Between the slots are marks 14 used for gaging purposes when it is desired to cut thin slices one-half the width of the ordinary slices. To cut such thin slices the tray is moved so that the back 10 registers with any of the marks and the forward part of the block cut in the ordinary manner. The 85 marks 14 can be stamped engraved or may be formed into grooves.

It will thus be seen that we have provided a simple, efficient and sanitary device for shipping and cutting blocks of ice-cream or the like into uniform slices. The slices cut by this method are not compressed and will retain their original bulk.

Having described our invention, we claim:

In an apparatus of the character described comprising a casing having a hinged end wall and side walls provided with parallel slots, a tray having an upstanding rear end movably retained in said body member for holding the product to be sliced, gage marks 95 100

on the inside of said side walls between said slots for gaging the thickness of a slice to be cut one-half the thickness of the ordinary slice, means for allowing the tray to be pushed outwardly, and a flanged cover for holding the said hinged end member in a closed position.

In testimony whereof we affix our signatures.

10

JOHN N. MOCKING.
MORRIS INDECH.
